SWING SEAT

Bobby L. Harness, 5052 Clark Drive,
Shawnee Mission, Kans. 66205

Filed June 22, 1967, Ser. No. 7,559

Term of patent 14 years

(Cl. D34—5)

Fig. 1.

Fig. 2.

Fig. 3.

Fig. 4.

Fig. 5.

FIG. 1 is a front perspective view of a playground swing embodying my design;

FIG. 2 is a side elevational view of same;

FIG. 3 is a front elevational view of same;

FIG. 4 is a rear elevational view of same; and

FIG. 5 is a sectional elevation taken along the line 5—5 of FIG. 3 in the direction of the arrows.

The dotted-line portions of the drawing showing a support are shown only for purposes of illustration.

I claim:

The ornamental design for a swing seat, as shown and described.
